H. A. HAYWARD.
FLUID PRESSURE GOVERNOR,
APPLICATION FILED SEPT. 22, 1916.

1,216,116.

Patented Feb. 13, 1917.

WITNESSES

UNITED STATES PATENT OFFICE.

HAROLD A. HAYWARD, OF NEW YORK, N. Y.

FLUID-PRESSURE GOVERNOR.

1,216,116.

Specification of Letters Patent. Patented Feb. 13, 1917.

Application filed September 22, 1916. Serial No. 121,607.

To all whom it may concern:

Be it known that I, HAROLD A. HAYWARD, a citizen of the United States, and a resident of the city of New York, borough of 5 Manhattan, in the county and State of New York, have invented a new and Improved Fluid-Pressure Governor, of which the following is a full, clear, and exact description.

This invention relates to fluid pressure governors and has particular reference to devices of this character adapted to automatically govern the flow of fluid and deliver the same at a substantially uniform pressure materially reduced from a higher 10 pressure of either regular or irregular tension.

More definitely stated the apparatus disclosed herein is designed more particularly for reducing the pressure of gas received 20 at high pressure from the source of supply and delivering the gas at a uniform pressure much reduced from the tension or pressure of the source. I wish it to be distinctly understood, however, that my device is adapted for use in the governing of 25 other species of fluids, either gas or liquid.

Among the objects of the invention is to provide a governor including a casing having an inlet and an outlet, the inlet being 30 guarded by an adjustable valve whereby the volume of the fluid admitted into the casing may be delicately controlled according to various original pressures.

Another object of the invention is to improve the facilities for delicately adjusting or varying the effective pressure of the fluid within the casing acting upon the inlet valve.

A further object of the invention is to 40 specifically improve the construction of the inlet valve and its seat, providing for a more convenient and effective action or manipulation thereof.

A still further object is to provide controlling mechanism including a main rigid base having inlet and outlet holes formed therethrough with their axes vertical parallel said base, carrying or supporting on one side thereof the main features of the 45 movable valve mechanism, a casing being provided for the purpose of inclosing the valve mechanism and carrying means to actuate the same according to a desired uniform low pressure for the outlet.

With the foregoing and other objects in view, the invention consists in the arrange-

ment and combination of parts described and claimed, and while the invention is not restricted to the exact details of construction disclosed or suggested herein, still for 60 the purpose of illustrating a practical embodiment thereof reference is had to the accompanying drawings, in which like reference characters designate the same parts in the several views, and in which—

Figure 1 is a vertical central longitudinal section on the line 1—1 of Fig. 2 of my improved device showing the parts in normal operative position;

Fig. 2 is a horizontal section on the line 70 2—2 of Fig. 1, and indicating the main valve mechanism in plan;

Fig. 3 is a plan view of the inner valve seat showing the screen therein;

Fig. 4 is a detail view of the diaphragm 75 hanger or link connecting the lever mechanism for governing the position of the inlet valve;

Fig. 5 is a transverse sectional detail on the line 5—5 of Fig. 2.

Referring now more particularly to the drawings, I call attention first to a strong rigid base 10 which may conveniently consist of a metal casing having ample strength for supporting the governor and valve mechanism with respect to a high pressure inlet pipe 11 and a reduced pressure outlet pipe 12, these pipes being shown as connected respectively in or to spuds 13 and 14 tapped into or through said base with their axes 80 vertical.

The spud 13 constitutes a valve seat, the active face of which is formed with a series of concentric corrugations or convolutions 15, the edges of which are shown lying in 95 the same plane and co-operating with a leather or other soft compressible gasket 16, cemented or otherwise secured to the bottom or active plane face of the valve 17, referred to hereinafter as the inlet valve.

The lower end of the spud 13 is counter-bored at 18 to admit the inlet pipe 11 and thereby provide a shoulder or seat 19 against which a strainer 20 is secured by the end of the inlet pipe. This strainer has the effect 105 of modifying to a certain extent the force of the pressure while the fluid is on the way through the restricted inlet 13', and it also serves as a means to prevent any coarse or heavy particles of extraneous material passing into the governor casing.

The casing referred to comprises two

parts 21 and 22 which may be made of any suitable design or from any desired material. Preferably, however, for the sake of strength, neatness of appearance and facility and cheapness of construction, I make the casing of sheet metal pressed or spun into the form indicated. The bottom section 21 is provided with two holes 13^a and 14^a adapted to receive the spuds 13 and 14 respectively therethrough and whereby the bottom section 21 of the casing is firmly and permanently locked or anchored to the bottom of the base stem or spud having an outwardly projecting shoulder for clamping the material surrounding each of the holes to the base. Gaskets 23 of any suitable nature may be provided to make tight joints at these points. It will be observed that one of the spuds is located centrally of the casing, while the other is adjacent one side thereof. The base is substantially co-extensive with the inside of the bottom section of the casing. One end of the inlet valve 17 is disposed close to or abutting against the inner vertical wall of the casing section 21, whereby the valve is retained in definite position and held from rotation around the vertical axis of the valve seat by contact between the curved casing wall and the curved end of the valve plate.

A pair of lugs or standards 24 carried by the base extend upwardly therefrom close to the valve seat 13, but between the valve seat and the central spud 14. The upper ends of these standards are provided with horizontally aligned holes through which a pivot pin 25 projects, the axis of the pivot pin being perpendicular to a straight line and joining the centers of the spuds. A standard or lug 26 is carried by the opposite end of the base and extends upwardly therefrom and has a hole through which a pivot pin 27 projects with its axis parallel to the axis of the pin 25.

45 The base, through the lugs just described, carries a lever mechanism of any suitable nature for controlling the position of the inlet valve 17. The lever mechanism shown herein and of a preferred nature includes a lever 28 of the first class journaled upon the pin 25 and having ball and socket connection 29 at its short arm with the effective center of the inlet 17. This connection with the inlet valve preferably includes a threaded stem acting through a main supporting nut 30 below the end of the arm, said stem having a slot 31 in its upper end for rotating the stem to vary the effective length of the stem, a lock nut 32 being provided to make such adjustment permanent. In this connection it is to be observed that the lever 28 is preferably formed of sheet metal, sufficient stiffness being provided by forming two downwardly projecting flanges

28'. The nut 30 fits between these flanges at 65 the short end of the lever and thereby is held from rotation while the stem is being turned. That portion of the lever 28 through which the pivot pin 25 passes is of wider structure than the end portions 70 whereby a greater stability for the lever is realized. The longer end or arm of the lever 28 has its downwardly projecting flanges 28' provided with longitudinal slots 75 33 which extend practically from the extreme end 28' of the lever adjacent the lug 26, inwardly toward the center of the lever system. These slots are in horizontal alignment with each other.

A secondary lever 34 of the second class 80 is pivoted at one end on the pin 27 while its free end is located approximately in the vertical center of the system and is pivotally connected to the lower end of a diaphragm hanger or link 35. The lever 34 85 comprises parallel side flanges lying in vertical planes on opposite sides of the longer end of the lever 28, said flanges being connected to each other at their pivoted end by a yoke 36 spanning the upper end 90 of the lug 26. Each of the flanges of the lever 34 is individually pivoted to one of the downwardly projecting legs 35' of the hanger by means of a short pivot 37. The free end of this lever 34, therefore, has 95 free movement up and down with respect to the adjacent part of the primary lever 28. The hanger is shown in detail in Fig. 4 and comprises in addition to the legs 35', a plate 35^a having a central hole for a 100 screw or other suitable fastener 38, upon opposite sides of which are formed a pair of lugs 39 struck downwardly and providing a seat for a non-rotary nut 40, with which said screw co-operates to bind a 105 weight or disk 41 to a flexible partition or diaphragm 42 secured firmly in place between the flanges 43 formed upon and extending outwardly from the casing sections 21 and 22. These flanges are preferably beaded, as indicated at 43', for the purpose of stiffening the same and through which fastening means 44 pass to lock the parts of the casing together.

The parallel flanges constituting the lever 115 or link 34 are provided with pairs of oppositely aligned holes 45, a series of such pairs of holes extending practically from one end of the lever to the other. A coupling pin 46 is passed through any selected 120 pair of holes 45 and the registering slots 33 of the primary lever, the position of the coupling pin with respect to the secondary lever determining the effective ratio between the power end of the lever 34 and the 125 valve end of the lever 28. The vertical movement of the hanger 35 is never very excessive, and hence the movement of the

hanger in an arc of a circle around the axis of the pin 27 may easily be accommodated by slight looseness in the pivot connections. Any of the pins 25, 27 or 46 may be provided at one end of the finger piece for convenience in manipulation and held temporarily in operative position by any suitable form of temporary fastener, such as a cotter pin 47.

10 The force of the weight 41 may be increased if desired by a spring 48 held centrally thereof by means of an adjustable screw 49 tapped through the center of the upper casing section 22 and held in place by a lock nut 50 to make such adjustment effective. This center screw 49 is provided with a vent 51 to maintain the upper portion of the casing under atmospheric pressure. I wish to emphasize that the adjustment of the inlet valve through the stem 29 provides for variation in the volume of fluid admitted into the casing; the adjustment of the screw 49 provides for a variation in the effective force of the counterbalance means acting upon the diaphragm, and the adjustment of the coupling pin 46 along the slots 33 provides directly for variation in the effective pressure of the diaphragm mechanism.

0 I claim:

1. In a fluid pressure governor, a casing provided with an inlet and an outlet, a valve for the inlet, a pivotally mounted lever connected with said valve, a diaphragm, a link pivoted to the casing at one end and extending thence along said lever, pivotal connections between the other end of the link and the diaphragm, one of said pivoted members having a longitudinal slot and the other having a series of holes extending along said slot, and a pivot member extending through said slot and in one of said holes to variably connect the link and lever together.

2. In a fluid pressure governor, the combination of a casing provided with an inlet and an outlet along the same side, a rigid base fitted within said casing side and having threaded openings registering with the respective casing openings, inlet and outlet spuds extending into the respective pairs of registering openings, locking the casing and base together, one of said spuds constituting a valve seat, a valve coöperating with said seat, said base having a plurality of standards projecting therefrom within the casing, primary and secondary lever members pivoted to said standards and lying one along the other between the standards, one of said lever members having a slot and the other having a series of holes arranged along the slot, a pivot member adapted to extend through the slot and in one of said holes to pivotally connect the lever members to-

gether, means connecting one of said lever members to the valve, and automatically actuated means connected to the other lever member to actuate the valve.

3. In a fluid pressure governor, a comparatively light sheet metal casing having a flat bottom provided with inlet and outlet openings in the same plane, a stiff base member having a flat bottom fitted squarely against the inner surface of the casing bottom and having inlet and outlet openings 75 registering with the casing openings, a pair of pipe connections fitted in said registering openings and serving to constitute through said base the means for supporting the entire governor, one of said connections constituting a valve seat, a valve within the casing coöperating with said valve seat and serving to control the inflow of fluid into the casing, a pair of approximately parallel lever members within the casing and pivotally connected to remote portions of said base, means to pivotally connect one of said lever members to said valve, automatic fluid actuated means connected to the other lever member, and means pivotally connecting 80 said lever members together whereby the action of the automatic means will be transmitted to the valve.

4. In a fluid pressure governor, a sheet metal casing having inlet and outlet openings in its bottom, a rigid base fitted against the inner surface of said bottom and having threaded openings registering respectively with said casing openings, a pair of shouleder spuds screwed into the respective pairs 95 of registering openings and serving to lock the casing and base together with tight joints, one of said spuds serving as a valve seat, a valve coöperating with said seat to control the flow of fluid into the casing, a 100 plurality of standards extending upwardly from opposite end portions of the base and having parallel pivot holes at their upper ends, a pair of approximately parallel lever members lying one along the other above 110 the base and pivoted respectively at their opposite ends in said pivot holes, one lever member overlapping the other, means connecting one lever member to the valve, automatic fluid actuated means connected to the 115 other lever member, and adjustable means to pivotally connect the overlapping portions of the lever members whereby the action of the automatic means is variably transmitted through the lever members to 120 the valve.

5. In a fluid pressure governor, a casing provided with an inlet and an outlet, a valve for the inlet, a pivotally mounted lever connected with said valve, said lever having a 125 slot arranged therein longitudinally, a diaphragm, a hanger connected with said diaphragm, a link pivotally connected with said

- 4
- hanger, means for pivotally connecting the free end of said link to said casing, and a member extending through the said slot and adjustably connected with said link, whereby the amount of movement transmitted from said link to said lever may be varied.
6. A fluid pressure governor comprising a casing having an inlet opening and an outlet opening, a valve for the inlet opening, a pivotally mounted lever connected with said valve and arranged to open and close the valve, said lever having a slot extending longitudinally thereof, a diaphragm, a pivotally mounted link having its free end pivotally connected with the diaphragm, and a member adjustably mounted on said link extending through said slot for transmitting motion from the link to the lever.
7. In a fluid pressure governor, a casing provided with an inlet opening and an outlet opening, a valve for the inlet opening, a lever connected with said valve for moving the valve to a closed and open position, said lever having a slot extending longitudinally thereof, a link pivotally connected to said casing, a diaphragm, means for connecting the one end of said lever to said diaphragm, whereby when the diaphragm is actuated the link will be moved pivotally, and an adjustable member connected with said link and extending through the slot in said lever.
8. In a fluid pressure governor, a casing provided with an inlet and an outlet, a valve for the inlet, a pivotally mounted lever connected with said valve for opening and closing the valve, said lever having a slot extending longitudinally thereof, a link pivotally mounted on said casing, said link having a plurality of apertures therein, a diaphragm actuated by pressure in the casing, means for pivotally connecting the free end of the link with said diaphragm whereby when said diaphragm is moved, said link will be moved pivotally, and a pin extending through the slot in said lever into one of the apertures in said link, said pin being arranged to fit into any of said apertures, whereby the lever and link are adjustably connected together for transmitting a predetermined movement to the valve for opening or closing the same.
9. A fluid pressure governor comprising a casing having a curved side wall and provided with inlet and outlet openings, a valve member for the inlet opening comprising a substantially flat plate formed with a socket and a curved projection extending along the curved wall aforesaid of the casing whereby the valve member is prevented from any rotary movement and is guided in its movement toward and from its seat, a pivotally mounted lever, a member connected with said lever provided with a ball fitting into said socket, whereby when said lever is moved in one direction, the valve is forced to its seat and by the use of the ball is permitted to automatically adjust itself to its seat, a diaphragm arranged in the casing, and means for connecting the diaphragm with the lever for opening and closing the valve.
10. In a fluid pressure governor of the character described, a casing provided with an inlet and an outlet, a valve member for the inlet, a pivotally mounted lever for operating said valve member, a link provided with a pair of arms straddling said lever, means for pivotally mounting one end of said link on said casing, a diaphragm actuated by a fluid in one direction, means for forcing the diaphragm in the opposite direction when the fluid has been reduced to a predetermined extent, means for connecting the free end of said link to said diaphragm, and an adjustable member mounted on said link and engaging said lever, whereby the movement of the diaphragm will be communicated to said lever for opening and closing said valve.

HAROLD A. HAYWARD.
